UNITED STATES PATENT OFFICE.

WILFORD L. SMITH AND FRANKLIN P. SMITH, OF WILMINGTON, DELAWARE.

RAIL-LOCK FOR RAILWAY-DRAWBRIDGES.

No. 862,358.

Specification of Letters Patent.

Patented Aug. 6, 1907.

Application filed April 25, 1907. Serial No. 370,132.

To all whom it may concern:

Be it known that we, WILFORD L. SMITH and FRANKLIN P. SMITH, both citizens of the United States of America, residing in Wilmington, in the county of

5 Newcastle and State of Delaware, have invented a certain new and useful Improvement in Rail-Locks for Railway-Drawbridges, of which the following is a true and exact description, reference being had to the accompanying drawings, which form a part thereof.

10 Our present invention relates to means for locking the movable rails of a drawbridge in alinement with the adjacent stationary rails.

In a drawbridge, as usually constructed, the outer ends of the rails on the draw or movable section of the 15 bridge are made movable relative to such bridge portion in order that the outer ends of the rails may be raised to clear the rails and the guides or chairs on the stationary part of the bridge or adjacent abutment when the draw is opened while the inner ends of the 20 rails are secured to the bridge structure.

The object of our present invention is the provision of locking means so constructed and disposed as to be entirely certain and secure in their operation. Such 25 certainty and security is, of course, desirable in the highest degree, because of the great loss of life and property liable to occur upon a failure of the rail locking means when trains pass over the bridge.

In carrying out our invention we attach locking devices to the track rails at the extreme ends of the draw 30 section of the bridge so that the locking devices have practically the same movement as the extreme ends of the rails and not merely a fraction thereof as is the case where the attaching devices are secured to the rails at some distance from the ends of the rails. We 35 also so shape and arrange the locking parts that they are not apt to get out of order and dispose them on the bridge structure so that they do not interfere with the necessary clearance and are not exposed to injurious contact with other parts.

40 The various features of novelty which characterize our invention are pointed out with particularity in the claims annexed to and forming a part of this specification. For a better understanding of our invention however and the advantages possessed by it, reference 45 may be had to the accompanying drawings and descriptive matter in which we have illustrated an embodiment of our invention.

Of the drawings, Figure 1 is a plan view of a portion of the bridge equipped with our invention. Fig. 2 is 50 an elevation of a portion of one end of the movable bridge section showing the rails in the locked position. Fig. 3 is a view similar to Fig. 2 showing the rails in the unlocked and elevated position. Fig. 4 is a perspective view showing a portion of one rail, the adjacent 55 locking tongue and the portion of the coöperating parts, the locking tongue being in the locked position. Fig.

5 is a view similar to Fig. 4 with the rail in the unlocked and elevated position. Fig. 6 is a partial section on the line 6—6 of Fig. 2, and Fig. 7 is an enlarged section on the line 7—7 of Fig. 3.

60

In the drawings, A, represents the movable section or draw proper of a swinging drawbridge and B represents the adjacent stationary bridge portion or abutment as the case may be. In the form shown in the drawings, the bridge is double tracked and is provided 65 with the usual end beams A' and ties A², some of which may be common to both sets of rails and some only to one set of rails; the ties and end beams are secured on the usual stringers A³. The track rails A⁴ are secured against the ties at points remote from the 70 end beam A', but adjacent the end beam the rails are free to move up from the bridge structure as is usual to permit the scarfed ends A⁵ to be raised above the corresponding scarfed ends of the rails B⁴ supported on the end beam B' and the ties G² of the stationary 75 bridge section or abutment B. The rails A⁴ are lifted from the ties A² by means of a suitably actuated lift beam A⁷ and are held against lateral displacement by means of the side flanges or chairs or shoes A⁶ secured to the ties. Both of the bridge sections are provided 80 with the usual alining guard rails A⁸ and B³, and the adjacent ends of the rails A⁴ and B⁴ are received in channeled chairs B⁵ carried by the bridge section B.

85 A locking tongue C is secured to each of the rails A⁴ at the outer surfaces of the end beam A'. As shown, the locking tongue C is provided with bent hook like projections C' at its upper end which embrace the two lower flanges or base of the rail. In practice, the parts are so shaped that the locking tongue has a certain slight capacity for motion relative to the rail so that the parts 90 may be easily assembled by sliding the tongue endwise on to the rail. In order that the tongues may turn relative to the rails through the slight angle necessary to preserve the vertical alinement of the body portions of the tongues as the rails are removed toward and away from the ties the under edges of the hooks C' are preferably rounded as shown at C⁵. Each locking tongue is provided on its back side with a groove C² for the locking bar and on its front side with a shoulder C⁴, which, in the form shown, is made by reducing the thickness of 95 the body portion of the tongue at a point slightly below the locking bar groove C². The portion of the locking tongue below the shoulder C⁴ slides in a pocket carried by a bar D⁷ extending parallel to the end beam and having a yoke member D⁸ riveted to the bar D⁷. The ends 100 of the bars D⁷ are secured into L shaped brackets D and D', each having a portion extending parallel to the locking tongue and another portion resting on the top of the end beam and extending parallel to the track rails. Each bracket consists of an L shaped part D² 105 next the beam, and another and generally similar part D³ secured on the top of the part D² by means of suit-

110

able rivets. As shown, the part D³ is offset at D⁴ so that the lower portion of this part is spaced away from the corresponding portion of the part D³. Below the offset portion D⁴, a roll D⁵ is journaled between the parts D² and D³, the roll forming the bottom of a pocket or passage D⁶ for the locking bar E. Between the lower ends of the parts D² and D³ of each bracket is secured one end of the corresponding bar D⁷. A spacing block D⁹ is inserted in the bracket D' where the space between the lower portions of the parts D² and D³ is greater than in the bracket D'.

The locking bar E for locking the tongues C in their lower position is arc shaped to correspond to the curvature of the outer surface of the end beam A' and passes through the pockets in the brackets D and D' resting on the rolls D⁵. The locking bar adjacent each locking tongue, a lug or projection E', preferably integral with the bar. The tongues are locked in position and released by moving the bar E in the direction of its length to move the projections E' into and out of the pockets or grooves C² formed in the tongues. As shown by the drawings, the body portion of the locking bar is to the rear of the back face of the locking tongue and is so proportioned that it can move readily in the pockets D⁶ of the brackets D but without lost motion. Similarly the bar and projections E' have a sliding fit in the pockets D⁶ of the brackets D' and the projections E' fill the pockets C² of the locking tongues in the locking position. By this arrangement the locking bar is properly supported and guided by the brackets while at the same time sufficient clearance is provided for easy operation of the locking bar.

The operation of the locking device will be readily understood from the foregoing.

35 The construction of the parts is such that the locking tongues may readily be arranged at the most favorable position, namely, at the extreme end of the movable portion of the bridge. As the locking bar is accurately guided and the coöperating locking shoulders on the locking tongue and locking bar are each rigid with the locking tongue and locking bar, it is impossible to move the locking bar into the locking position except when the rails are down in their proper position. In practice, we have found that the locking bar cannot be moved 45 to the locking position when the end of any rail is but slightly, say an eighth of an inch, above its proper position. This is an important feature, since while a displacement of a rail no greater than an eighth of an inch or thereabout would not directly tend to cause the derailment of a train under ordinary conditions, it is apt to result in a broken rail, always a serious annoyance and liable to produce very disastrous effects. Preferably the edges of the projections E' and pockets C² are rounded but little if at all so that the projections will 50 either readily enter the pockets C² or be definitely held out thus avoiding liability of forcing and thereby injuring the parts.

60 The construction and arrangement of the parts is such that the locking tongues can be located at the extreme end of the draw without interfering with the necessary clearance between the movable and stationary portions of the bridge and the brackets, locking tongue etc., may be recessed in the end beam, as shown best in Fig. 6. In the form shown it will be observed that the 65 brackets are partly sunk into the end beam and that the

locking bar is located in a rabbet formed in the end beam thus protecting the locking bar from accidental contact with parts liable to injure it.

It will be understood that in practice the operating rod E⁴ for operating the locking bar through the bell crank lever E³ and link E² is interlocked with the engine, not shown, mounted on the movable portion of the drawbridge for moving the draw and for operating the lifting beam A⁷ and locking the movable bridge structure in place and with the track controlling signals 75 so that the signals cannot be set in the clear position except when all the rails are down and locked in place by the locking bar, and the locking bar can not be removed from the unlocking position to the locking position except when the drawbridge is turned and locked to bring 80 the rails A⁴ in alignment with the rails B⁴.

Should the locking tongue break loose from its rail, wholly or partially, as by the failure of one only of the hooks C¹, the locking tongue will have the upper end of the groove C² brought below the corresponding projection E when the rails are down thereby preventing the actuation of the locking bar. The shoulder C⁴ is so located relative to the upper edges of the bar D⁷ and yoke D⁸ that the tongue, when completely broken loose from the rail will have its upper portion in line 90 with the projection E' and will therefore prevent the locking bar from being moved to the locking position. In the form shown, the locking bar E and projections E¹ are in one integral structure but it will be understood that the bar may readily be formed of sections 95 rigidly connected together when necessary as where the signaling system employed requires that the track rails should be insulated from each other.

Having now described our invention, what we claim as new and desire to secure by Letters Patent is,

1. In combination with the swinging section of a railway drawbridge structure and track rails carried by said movable section with their ends projecting by the ends of said bridge section proper and movable away from the level of the section to clear the adjacent stationary rails, of locking means for securing the rail in place when the draw is closed, said means comprising a locking tongue secured to and depending from each rail at the end of the draw, guides for each locking tongue located on the end beam of the bridge and a locking bar extending along the front side of the beam and provided with shoulders rigid on the bar and coöperating with shoulders rigid on the locking tongue.

2. In combination with the swinging section of a railway drawbridge structure having end beams with outer curved surfaces and track rails carried by said movable section with their ends projecting by the ends of said bridge section proper and movable away from the level of the section to clear the adjacent stationary rails, of locking means for securing the rails in place when the draw is closed, said means comprising a locking tongue secured to and depending from each rail at the end of the draw, guides for each locking tongue located on the end beam of the bridge and a curved locking bar extending along the front side of the beam and provided with shoulders rigid on the bar and coöperating with shoulders rigid on the locking tongue.

3. In combination in a railway bridge structure having a swinging section provided with an end beam having its outer surface curved and formed with a rabbet, of a locking tongue secured to each track rail and a curved locking bar coöperating with all the locking tongues and located in the rabbet formed in the curved face of the end beam.

4. In combination with the swinging section of a railway drawbridge having the outer ends of its track rails movable, a locking tongue secured to and extending downward beneath each track rail, coöperating with the locking

tongues at one end of the bridge section, a locking bar, and guides for each locking tongue, comprising two brackets, one at each side of the locking tongue, each bracket having a portion extending down the front face of the end beam of the bridge and another portion resting on the beam, and also having a pocket for the locking bar and a crosspiece connecting the lower ends of the brackets and provided with a pocket for the locking tongue.

5. In combination with the swinging section of a rail-way drawbridge having the outer ends of its track rails movable, of a locking tongue for engaging each track rail, each tongue having the rail engaging hooks C¹ with rounded edges C⁵, the locking bar pocket C², and the shoul-

der C⁴, the locking bar E having the projections E¹ adapted to enter the pockets C³, the brackets D and D¹ secured 15 to the end beam and provided with passages receiving the locking bar and the crossbar D⁷, connecting the brackets D and D¹ and yoke D⁸, the crossbar and yoke having the pocket for receiving the portion of the locking tongue below the shoulder C⁴.
